SNOWDEN B. REDFIELD, OF EASTON, PENNSYLVANIA, ASSIGNEES TO INGERSOLL-RAND COMPANY, OF JERSEY CITY, NEW JERSEY, A CORPORATION OF NEW JERSEY.

CENTRALIZER INTERLOCKING CONTROL FOR MULTISTAGE COMPRESSORS.

Application filed October 30, 1926. Serial No. 145,243.

This invention relates to compressors, but more particularly to an unloading device for compressors of the multi-stage type.

The objects of the invention are to enable the cylinders of the compressor to be selectively loaded and unloaded by fluid actuated means whenever it is desirable to change the capacity or the working pressure, to conveniently group the valves which control the admission and exhaust of pressure fluid to and from the load controlling means, and to render the controlling mechanism interlocking, so that in unloading cylinders operating at lower pressures, another cylinder operating at a higher pressure will be simultaneously partially unloaded to compensate for the reduction in the discharge volume of the lower pressure cylinders, also to prevent such a combination of unloader movements as would be undesirable or even dangerous.

Other objects will be in part obvious and in part pointed out hereinafter.

The invention consists of the combination of elements and arrangement of parts having the general mode of operation substantially as hereinafter described and more particularly pointed out in the appended claims and illustrated in the accompanying drawings, in which—

Figure 1 is an elevation of a multi-stage compressor having the invention applied thereto;

Figure 2 is a top plan view of the compressor;

Figure 3 is a sectional elevation partly diagrammatic taken on the line 3—3 of Figure 2 looking in the direction of the arrows;

Figure 4 is an enlarged sectional elevation of a portion of the third stage cylinder and its controlling mechanism;

Figure 5 is a sectional elevation of the fourth stage cylinder and its controlling valve;

Figure 6 is a sectional view of the throttle valve and its handle taken through Figure 1 on the line 6—6 looking in the direction of the arrows, and Figure 7 is an enlarged detail view of one of the inlet valves and its unloader piston.

Referring to the drawings, the invention is shown embodied in a compressor designated generally by A. The compressor illustrated is of the multi-stage type commonly used in marine craft, as for instance, sub-

55 marines in which a portion of the compressed air is utilized by the engines of the submarine and a portion of the pressure fluid is compressed to a higher pressure for charging the torpedo bottles. The compressor A in this instance has a pair of cylinders 60 B and C preferably arranged side by side and mounted on suitable base plates D and E respectively.

Within the cylinder B is a piston F to divide said cylinder into first and second stage cylinder chambers G and H respectively. In like manner a piston F is provided for the cylinder C to divide said cylinder into a first stage cylinder chamber J and a second stage cylinder chamber K in the upper and lower ends respectively of the cylinder C. The pistons F may be driven by any suitable prime mover to which they may be connected by connected rods L operatively connected to the pistons by piston pins O.

55 The admission of atmospheric air flowing through intake pipes 2 to the first stage cylinder chambers G and J is effected through inlet plate valves P and Q of any suitable 60 type seated in valve boxes R and S supported in this instance by the cylinders B and C respectively. The air drawn into the first stage cylinders is compressed by the pistons F and is discharged through plate discharge 65 valves T and U also seated in the valve boxes R and S respectively. The air thus compressed in the first stage cylinders passes into a manifold V interposed between the valve boxes R and S and thence through a 70 pipe W into an intercooler X.

75 Pressure fluid from the intercooler X is conveyed therefrom by a pipe Y having branches Z and 7 which lead to the second stage cylinder chambers H and K respectively. The admission of pressure fluid into the second stage cylinder chambers H and K is controlled by inlet plate valves c and d of a well known type. Discharge plate valves T and U which control the exhaust 80 of pressure fluid from the cylinder chambers H and K into chambers e formed in the cylinders B and C from whence the pressure fluid may pass through a pipe f which connects the chambers e and thence through a 85 pipe g into an intercooler h.

In order to compress the pressure fluid in the intercooler h to a pressure suitable for

use in mechanism requiring fluid of higher pressure, such as internal combustion engines in which the fuel is injected into the combustion chamber under pressure, a third stage cylinder *j* is arranged in tandem with the cylinder *C* and in this instance is shown as being formed integrally with the valve box *S*. The cylinder *j* is in communication with the intercooler *h* through a pipe *k* and the admission of pressure fluid from the pipe *k* into the cylinder *j* is controlled by an inlet plate valve *o* seated in a head *p* supported by the cylinder *j*. The pressure fluid thus entering the cylinder *j* is compressed therein to a higher pressure by a piston *q* connected to, or as shown, formed integrally with the piston *F* in the cylinder *C* and is discharged through a discharge valve *r*, a passage *s* in the head *p* and thence through a conduit *t* into an intercooler *u*.

Formed integrally with the valve box *R* is a fourth or final stage cylinder *v* having a guide bushing *w* in which reciprocates a piston *x* connected at one end to the end of the piston *F* in the cylinder *B* to which it is secured by means of a nut *y*. A head *z* supported by the cylinder *v* is provided with an inlet valve *3* and a discharge valve *4* of well known types for controlling the admission of pressure fluid into the cylinder *v* and the exhaust of pressure fluid therefrom. The inlet valve *3* in this instance controls an inlet passage *5* formed in the head *z* for conveying pressure fluid into the cylinder *v* and the discharge valve controls an exhaust passage *6* formed in the head *z* for conveying the exhaust pressure fluid from the cylinder *v*.

In order to provide a novel and simple controlling means for loading and unloading the several cylinders of the compressor, the inlet valves *P* and *Q* of the first stage cylinder chambers *G* and *J* are in this instance provided with unloader pistons *7* slideable in covers *8* seated on the valve boxes *R* and *S*. The unloading pistons have depending fingers *9* which, when the pistons *7* are in their inoperative positions, extend to a point slightly removed from the valve plates *10* of the valves *P* and *Q*.

Similar means are provided for the valves *c* and *d* in the cylinder chambers *H* and *K*, although in this instance the pistons *7* are guided in housings *11* interposed between the inlet valves and covers *12* which form closures for the housings *11*. The unloading pistons *7* are of a well known type in which springs *B'* (Fig. 7) are provided for normally holding the fingers *9* out of contact with the valve plates *10*.

Pressure fluid for actuating the pistons *7* is conveyed to the cylinders wherein the said pistons *7* reciprocate by a pipe *13* having branches *14* and *15* connecting the pipe *13* with the pistons *7* which control the inlet

valves *Q* and *d*. The pipe *13* in this instance leads from a valve chest *16* in which is arranged a manipulating valve *17* for controlling the admission of air from a service pipe *18* into the said pipe *13*. In like manner a pipe *19* is provided for conveying pressure fluid from the valve chest *16* to the unloader pistons *7* which control the inlet valves *P* and *c* of the cylinder chambers *G* and *H*.⁷⁵

In order that the third stage cylinders *j* may also be partly unloaded whenever the chambers of the cylinder *B* or *C* are unloaded, a clearance valve *20* is arranged slidably in a valve guide *21* inserted in the head *p* to control a port *22* in the cylinder *j*. A distance piece *23* is in this instance secured to the valve guide *21* and supports at its outer end a cylinder *24* in which is arranged a fluid actuated piston *25* adapted to bear against a stem *26* of the clearance valve *20* for holding the said clearance valve closed during the loaded period of the cylinder *j*.⁸⁰

Pressure fluid for actuating the piston *25* and thus also the valve *20* is conveyed to the cylinder *24* through a pipe *27* leading from the valve chest *16*. The admission of pressure fluid to the pipe *27* is also controlled by the manipulating valve *17*, the pipe *27* being so connected to the chest *16* that when the two first stage, the two second stage and the third stage cylinders are operating under full load conditions, there will be a constant admission of pressure fluid from the pipe *18* through a passage *28* in the valve *17* and through the pipe *27* into the cylinder *24*.⁸⁵

In the present instance the manipulating valve *17* is provided with a side recess *29* which, when the manipulating valve is turned in one direction, will establish communication between the pipe *18* and a passage *30* leading to the pipe *19*. A similar recess *31* is formed in the opposite side of the manipulating valve *17* for establishing communication between the pipe *18* and the pipe *13* when the manipulating valve *17* is turned to another limiting position.¹⁰⁵

The positions which the manipulating valve *17* may occupy for admitting pressure fluid from the pipe *18* to the several pipes *13*, *27*, and *19* are indicated at *32*, *33*, and *34* respectively on a dial *35* formed integrally with a bracket *36* on which the valve chest *16* is mounted.¹¹⁵

Convenient means are provided for manipulating the manipulating valve *17*. For this purpose a manipulating handle *37* is secured to an extension *38* of the manipulating valve *17* and is held in assembled position by a pin *39* which extends through the extension *38* and the handle *37*. A pointer *40* is preferably formed integrally with the handle *37* and is of a length to extend to a point adjacent the indicators *32*, *33* and *34*.¹²⁵

for indicating the positions the manipulating valve occupies in practice.

In order that the manipulating valve 17 may be securely held in placed position, a release handle 41 is pivoted thereto to cooperate with slots 42 in the valve chest 16 suitably located with respect to the different positions of the manipulating valve. A spring 43 seated in the handle 37 bears constantly against the release handle for holding said handle in engagement with the slots 42.

Formed in the head p is a clearance pocket 44 from which leads a vent 45 controlled in this instance by an equalizer valve 46 slideable in a valve chest 47 secured to the head p in any suitable manner. A passage 48 formed transversely through the equalizer valve 46 communicates with a passage 49 leading to the rearward end of the valve 46 to permit the entrance of pressure fluid into a chamber 50, wherein the said valve is adapted to reciprocate for normally holding said valve closed. Pressure fluid thus acting against the valve for the purpose described is also augmented by a spring 51 constantly bearing on the valve for holding it to its seat. In the present instance an adjusting plug 52 carrying a spring seat 53 for one end of the spring 51 is screwed into the end of the valve chest 47 for adjusting the tension of the spring 51. A cap nut 54 screwed on the end of the adjusting plug 52 serves on the dual purpose of locking the adjusting nut in position and also seals the chamber 50. A pipe 55 leading from the valve chest 47 serves to convey pressure fluid from the chamber 50 to the passage s in the head p whenever the equalizer valve is unseated by pressure fluid in the clearance pocket 44.

An intake unloader 56 is provided for unloading and loading the fourth stage cylinder v . This intake unloader comprises a bracket 57 seated on the head z and has a passage 58 in communication with a pipe 59 leading from the intercooler u . Pressure fluid thus flowing from the intercooler u through the pipe 59 and the passage 58 is conveyed through a passage 60 in the bracket 57 which communicates with the passage 5 in the head z . A bore 61 is formed in the bracket 57 preferably in line with the passage 58 to receive a valve guide 62 bored to receive slidably a plunger 63 which cooperates with a valve seat 64 in the valve guide 62 for controlling the flow of pressure fluid from the passage 58 into the passage 60 and, consequently, into the cylinder v .

Any suitable and convenient means may be provided for securing the valve guide in the bore 61. In the present instance an externally threaded nut 65 is bored to receive slidably the valve guide 62 and is screwed into a threaded aperture 66 in the bracket 57. A flange 67 formed in the outer end of the

nut 65 abuts a shoulder 68 of the valve guide 62 for holding the valve guide in position.

In order to prevent the escape of any pressure fluid which may leak along the plunger 63 to the atmosphere, a check valve 69 is placed in the valve guide 62 rearwardly of the plunger 63 to rest on a seat 70 in the valve guide when the plunger 63 is opened to admit pressure fluid from the intercooler u into the cylinder v .

75

Supported by the bracket 57 is an unloader cylinder 71 having a cover 72 secured to the outer end thereof in any suitable manner. In this unloader cylinder 71 is arranged a piston 73 which abuts a valve stem 74 of the check valve 69 and is adapted to slide in a reciprocable piston head 75 arranged slidably in the cylinder 71. Packing members 76 interposed between the piston head 75 and a flange 77 of the piston 73 are compressed by the piston head 75 and the piston 73 to prevent leakage of pressure fluid from the cylinder 71.

To the end that the cylinder v may be short circuited or vented to the atmosphere during its unloaded period, a discharge unloader comprising a body 78 is supported by the head z . The body 78 has a passage 79 which communicates with a passage 80 in the head z leading from the passage 6, communication between the passages 6 and 80 being controlled by the discharge valve 4.

Disposed in a bore 81 of the body 78 is a valve cage 82 in which is arranged a valve 83 to control a passage 84 communicating with the passage 79. The valve 83 in this instance has an end head 85 which is adapted to abut a piston 86 slideable in a bore 87 of a bushing 88. The bushing 88 in this instance also serves to hold the valve cage 82 in assembled position. A recess 89 is formed in the inner end of the piston 86 to receive a spring 90 seated at one end against the end wall of the recess 89 and with its other end on the head 85 of the valve 83. The bushing 88 and the valve cage 82 may be held securely in assembled position in any suitable manner. In the present instance a collar 91 is arranged about the bushing 88 to abut a flange 92 of the said bushing and bolts 93 extending through the collar 91 are screwed into the end of the body 78.

A closure for the end of the bushing 88 is in this instance provided in the form of a plug 94 having a passage 95 which communicates with the bore 87 of the bushing 88. A pipe 96 leading from the passage 60 in the bracket 57 to the plug 94 serves to convey pressure fluid to the bore 87 for actuating the piston 86 to close the valve 83.

125

The means whereby pressure fluid may be admitted into the cylinder 71 to actuate the piston head 75 and the piston 73 to close the plunger 63 in this instance consists of a pipe 97 leading from a valve chest 98

130

mounted on the bracket 36 to the cylinder 71. The valve chest 98 serves as a housing for a manipulating valve 99 having a central passage 100 through which pressure fluid may flow from a branch 101 of the service pipe 18 into the pipe 97. A recess 102 formed in the side of the manipulating valve 99 is adapted to establish communication between the pipe 97 and an exhaust port 103 in the valve chest 98 for exhausting pressure fluid from the cylinder 71 to the atmosphere. The manipulating valve 99, like the manipulating valve 17, is also provided with a handle 37 for rotating the said manipulating valve and the pointer 40 to cooperate with indicators 104 and 105 of a dial plate 106 for indicating the positions which the valve is intended to occupy in practice.

In the present instance the regulator body 78 also acts as a housing for a check valve 107 of a known type slidable in a valve seat 108 to control communication between the passage 79 and a discharge passage 109 in the body 78. A spring 110 acting against the valve 107 acts to hold the valve closed for preventing the return of pressure fluid from a final receiver tank 111 communicating in this instance with the passage 109 through a pipe 112.

The operation of the device is as follows: Let it be assumed that it is intended to operate the compressor under full load conditions. In such case the manipulating valves 17 and 99 will occupy the positions illustrated in Figures 3, 4 and 5. In these positions of the valves pressure fluid will flow from the service pipe 18 through the passage 28 of the valve 17 and through the pipe 27 into the cylinder 24 to act against the piston 25 for holding the valve 20 closed. When the valve 17 occupies this position, the pipes 13 and 19 will be opened to the atmosphere through the recesses 31 and 29 and through exhaust ports 113 and 114 respectively in the valve chest 16. It will therefore be seen that the inlet valves of the first and second stage cylinders are free to function in their normal manner without being impeded by the fingers 9 of the unloader pistons 7.

When operating under full load, the unloader cylinder 71 is also open to the atmosphere through the pipe 97, the recess 102 in the valve 99 and through the port 103 in the valve chest 98, thus permitting the plunger 63 to occupy its open position for admitting pressure fluid from the passage 58 into the passage 60 and thence through the passage 5 into the cylinder *v*. While the plunger 63 is open, a portion of the pressure fluid entering the passage 60 from the passage 58 flows through the pipe 96 and through the passage 95 in the plug 94 and acting against the piston 86 forces the valve 83 to its seat and thus cuts off communica-

tion between the passage 79 of the regulator body 78 and an atmospheric vent 115 in said body 78.

If now, for well known reasons, it be desired to unload the fourth stage cylinder *v*, the manipulating valve 99 may be rotated to carry the pointer 40 to the indicator 105. In this position of the manipulating valve 99, the passage 100 will establish communication between the pipe 101 and the pipe 97 and pressure fluid will thus flow into the cylinder 71 and, due to the preponderance of area of the piston head 75 over the end of the plunger 63, will force said plunger to its seat against the relatively higher pressure flowing from the intercooler *u*. In this way communication between the intercooler *u* and the cylinder *v* will be cut-off and thus also the supply of pressure fluid acting against the piston 86 in the bushing 88 will be cut-off.

After the supply of pressure fluid to the cylinder *v* has been cut-off, the piston *x* will draw a vacuum and any slight amount of air which might find its way into the cylinder *v* will be exhausted through the passages 6, 80 and 79 and through the port 84 to move the valve 83 from its closed position and thence escape to the atmosphere through the vent 115. When the fourth stage cylinder *v* is operating under these conditions, the spring 90 in the piston 86 will force the piston 86 and the valve 83 apart so that in the absence of pressure fluid in the bore 87 of the bushing 88, the valve 83 will function as an ordinary check valve to allow the passage of air from the cylinder to the atmosphere through the vent 115 and to prevent the admission of atmospheric air into the passages 79 and 80.

Whenever the compressed air delivered from the third stage cylinder to the receiver tank or intercooler *u* exceeds a certain predetermined pressure and it is found desirable to reduce the volume discharged into the receiver tank, the cylinder chambers in one or the other of the cylinders *B* and *C* may be unloaded until the pressure in the receiver tank has been reduced to a desired value. Let it be assumed then that it be decided to unload the first stage cylinder chamber *G* and the intermediate stage cylinder *H*. To accomplish this the manipulating valve 17 may be rotated so that the pointer 40 will coincide with the indicator 34. In this position of the manipulating valve 17, pressure fluid from the pipe 18 will pass through the recess 29, the passage 30 in the valve chest and through the pipe 19 to act upon the ends of the unloader pistons 7. These pistons 7 will be thus forced forwardly so that the fingers 9 will bear upon the valve plates 10 and hold the said valve plates open. In this way the piston *F* in the cylinder *B* will reciprocate

in the cylinder C without doing any actual work of compression.

It will be noted that when the manipulating valve 17 has been rotated to the position for admitting pressure fluid into the pipe 19, the passage 28 in the manipulating valve will be moved out of registry with the pipes 27 and 18 and the pressure fluid previously admitted into the cylinder 24 will be then exhausted to the atmosphere through the pipe 27, the recess 31 and through the exhaust port 113 in the valve chest 16. By thus exhausting the pressure fluid from the cylinder 24, the valve 20 will be permitted to open so that a portion of the air in the cylinder j may pass into the clearance pocket 44 while the remaining portion is, of course, exhausted through the exhaust valve r to flow through the passage s and the pipe t into the intercooler u.

While the manipulating valve 17 is in the position described with pointer at position 34, the unloader pistons 7 of cylinders J and K will be in the out position due to exhausting of air behind them through the pipe 13, passage 31 and atmospheric vent 113. Thus the inlet valves Q and d will function to allow the cylinders J and K to operate under full load.

Frequently in manœuvring vessels of the type employing compressors to which the present invention is applied, it so happens that sudden unusual demands are made on the volume of compressed air in the receiver tank u, thus causing a considerable drop in pressure in said receiver tank as well as in the cylinder j. If, then, immediately prior to such demand, the cylinder j has been operating at one-half load and discharging into the clearance pocket 44, the clearance valve 20 will close immediately upon the occurrence of a drop in pressure in the cylinder j. With these conditions obtaining the pressure in the clearance pocket 44 may be of higher value than the pressure in the cylinder j and it is possible that the clearance valve 20 may be held shut by the pressure acting on the differential area of the reverse side of the valve 20 so that it will not open when pressure fluid is exhausted from the cylinder 24. However, with the pressure fluid in the receiver tank, as well as in the pipe t and the passage s, of lower value than the pressure entrapped in the clearance pocket 44, the equalizer valve 46 will open and the entrapped pressure fluid will flow from the clearance pocket 44 through the pipe 45 and the pipe 55 into the passage s.

The cylinder chambers J and K of the cylinder C may be unloaded in the manner described in connection with the cylinder chambers G and H, it being merely necessary to rotate the manipulating valve 17 so that the recess 31 in the manipulating valve

registers with the service pipe 18 and with the pipe 13 for admitting pressure fluid to act against the unloader pistons 7 of the inlet valves Q and d.

The above described invention has been found to be unusually efficient in operation. This is due largely to the manner in which the several cylinders comprising the first, second and third stages of the compressor may be unloaded or loaded by a single valve conveniently and centrally located on the compressor. The means, such as the valve 17 and the various unloading devices, provided for controlling the loading of the different cylinders is, in effect, interlocking, that is the unloading devices of the several cylinders will be caused to function in the proper order and at the most suitable period in the loading and unloading operations. For instance, when the valve 17 is rotated to unload either of the first and second stage cylinders, the third stage cylinder j will simultaneously be partially unloaded to compensate for the reduction in the load of the lower stage cylinders. Due to this fact the uncertainty heretofore experienced as to the proper functioning of the unloading devices by the operation of a multiplicity of control valves, handles and the like has been entirely eliminated. The positions which the manipulating valve 17 is supposed to occupy for unloading or loading the several stages is plainly indicated on the dial 35 and the manipulating valve 17 may therefore be freely manipulated without causing injury to the compressor.

I claim:

1. In a multi-stage compressor, the combination of cylinders operating at different pressures, fluid actuated means for loading and unloading the cylinders, and means for selectively controlling the admission and exhaust of pressure fluid to and from said fluid actuated means.

2. In a multi-stage compressor, the combination of cylinders operating at different pressures, fluid actuated means for loading and unloading the cylinders, and manually operable means for selectively controlling the admission and exhaust of pressure fluid to and from said fluid actuated means.

3. In a multi-stage compressor, the combination of cylinders operating at different pressures, fluid actuated means in the cylinders for loading and unloading the cylinders, and centrally located interlocking means remote from the cylinders for selectively controlling the admission and exhaust of pressure fluid to and from said fluid actuated means.

4. In a multi-stage compressor, the combination of a pair of cylinders operating at a low pressure, a cylinder operating at a higher pressure, a pair of intermediate pressure cylinders, and fluid actuated means for

simultaneously unloading a low pressure cylinder and an intermediate cylinder and for partially unloading the higher pressure cylinder.

5. In a multi-stage compressor, the combination of a pair of low pressure cylinders, a pair of intermediate cylinders connected to receive pressure fluid from the low pressure cylinders, a higher pressure cylinder connected to receive pressure fluid from the intermediate cylinders, inlet valves for the cylinders, pressure actuated means for unseating the inlet valves of the low and intermediate cylinders, a clearance valve for the higher pressure cylinder normally held closed by pressure fluid, and a manipulating valve rotatable to one position for admitting pressure fluid to the pressure actuated means for holding the inlet valves at one low pressure cylinder and one intermediate cylinder open to unload said cylinders and for simultaneously exhausting pressure fluid acting upon the clearance valve for partially unloading the higher pressure cylinder, said manipulating valve also being rotatable to another position for admitting pressure fluid to the pressure actuated means for holding the inlet valves of the other low pressure and intermediate pressure cylinders open and for simultaneously exhausting pressure fluid acting upon the clearance valve for partially unloading the higher pressure cylinder.

6. In a multi-stage compressor, the combination of a pair of first stage cylinders, a pair of second stage cylinders connected to receive pressure fluid from the first stage cylinders, a third stage cylinder connected to receive pressure fluid from the second stage cylinders, a fourth stage cylinder connected to receive pressure fluid from the third stage cylinder, pressure actuated means for controlling communication between the third and fourth stage cylinders, and means for selectively controlling the admission of pressure fluid to the pressure actuated means for unloading the fourth stage cylinder.

7. In a multi-stage compressor, the combination of a pair of first stage cylinders, a pair of second stage cylinders connected to receive pressure fluid from the first stage cylinders, a third stage cylinder connected to receive pressure fluid from the second

stage cylinders, a fourth stage cylinder connected to receive pressure fluid from the third stage cylinder, pressure actuated means for controlling communication between the third and fourth stage cylinders, and a manipulating valve rotatable to one position for admitting pressure to the pressure actuated means for unloading the fourth stage cylinder, said manipulating valve also being rotatable to another position to exhaust pressure fluid from the pressure actuated means for loading the fourth stage cylinder.

8. In a multi-stage compressor, the combination of a final stage cylinder and cylinders operating at lower pressures, means for conveying pressure fluid from a lower stage cylinder to the final stage cylinder, an unloader cylinder, a pressure fluid actuated plunger in the unloader cylinder for controlling the admission of pressure fluid from said means to the final stage cylinder, a manually operable valve controlling the admission of pressure fluid into the unloader cylinder to close the plunger for unloading the final stage cylinder, and means associated with the final stage cylinder for automatically and interlockingly establishing communication between the said cylinder and the atmosphere during the unloaded period of the final stage cylinder.

9. In a multi-stage compressor, the combination of cylinders operating at different pressures, connections for establishing communication between cylinders of successive stages, a valve chest, a valve in said chest adapted to establish communication between the cylinder operating at highest pressure and the atmosphere, said valve being held closed by pressure fluid during the operation of the high pressure cylinder, an unloader cylinder, a plunger in the unloader cylinder to control the admission of pressure fluid into the high pressure cylinder and into the valve chest, and a manually operable valve controlling the admission and exhaust of pressure fluid to and from the unloader cylinder to close and open the plunger for unloading and loading the high pressure cylinder.

In testimony whereof I have signed this specification.

SNOWDEN B. REDFIELD.
